(57) CLAIM

The ornamental design for mittens, as shown and described.

DESCRIPTION

FIG. 1 is a perspective view of the left-hand and right-hand mittens of my design, with the right-hand mitten being shown in a configuration whereby the fingers of a wearer may be exposed, and the left-hand mitten being shown in a configuration whereby the fingers of a wearer are covered; FIG. 2 is a perspective view of the left-hand mitten of my design;

FIG. 3 is a front elevation view of the left-hand mitten of my design;

FIG. 4 is a side elevation view of the left-hand mitten of my design;

FIG. 5 is a side elevation view of the left-hand mitten of my design, taken from the opposite side of that shown in FIG. 4;

FIG. 6 is a rear elevation view of the left-hand mitten of my design, taken from the opposite side of that shown in FIG. 3;

FIG. 7 is a top view of the left-hand mitten of my design; FIG. 8 is a bottom view of the left-hand mitten of my design; FIG. 9 shows the mitten of FIG. 2 in a configuration whereby the fingers of a wearer may be exposed;

FIG. 10 shows the mitten of FIG. 3 in a configuration whereby the fingers of a wearer may be exposed;

FIG. 11 shows the mitten of FIG. 4 in a configuration whereby the fingers of a wearer may be exposed;

FIG. 12 shows the mitten of FIG. 5 in a configuration whereby the fingers of a wearer may be exposed;

FIG. 13 shows the mitten of FIG. 6 in a configuration whereby the fingers of a wearer may be exposed;

FIG. 14 shows the mitten of FIG. 7 in a configuration whereby the fingers of a wearer may be exposed; and,

FIG. 15 shows the mitten of FIG. 8 in a configuration whereby the fingers of a wearer may be exposed.

The broken line disclosure in the drawings depicts environmental subject matter forming no part of the claimed design. In the drawings above, the appearance of the un-depicted right-hand mitten is understood to be a mirror-image of the depicted mitten.
